UNITED STATES PATENT OFFICE.

HAYDN BROWN, OF SURBITON HILL, ENGLAND.

SUTURE-CLAMP.

SPECIFICATION forming part of Letters Patent No. 709,392, dated September 16, 1902.

Application filed May 6, 1902. Serial No. 106,218. (No model.)

To all whom it may concern:

Be it known that I, HAYDN BROWN, a subject of the King of Great Britain and Ireland, residing at Mount Nelson, King Charles Road, 5 Surbiton Hill, in the county of Surrey, England, have invented a certain new and useful Improved Suture-Clamp; and I do hereby declare the following to be a full, clear, and exact description of the invention, such as will 10 enable others skilled in the art to which it appertains to make and use the same.

My invention has for its especial object to provide means for use in substitution for sewing for keeping in apposition the edges of 15 surgical incisions and wounds, so that they join in healing; but the devices according to my invention may be used for other clamping or binding purposes. For simplicity of description I will presume that the devices 20 are to be applied in keeping in apposition the edges of surgical incisions, as from this description of its use its general application will also be understood.

The clamp or binding device according to 25 my invention consists of two sharpened prongs connected by a bridge-piece or cross-bar, the said sharpened prongs being so curved each in the same direction as the other that the clamp or binder can be inserted and 30 withdrawn by a movement of rotation. For this purpose the two prongs are made semi-circles or portions of circles, both having the same radius and lying in parallel planes, and are connected by a bridge-piece at right 35 angles to those planes, such connecting-bridge being preferably at the circumference of these semicircles, so that by means of the clamp grasping this bridge-piece the sharpened prongs by the movement of rotation will simultaneously penetrate the flesh on the opposite sides of the incision and when 40 the said prongs are fully inserted the bridge-piece or cross-bar lying across the incision, so that the clamp or binder holds the edges 45 of the incision in apposition until they have joined by healing, when the clamp or binder can be readily removed by a movement of rotation the reverse of that applied in inserting the clamp or binder.

50 The curved prongs prevent the clamp or binder from accidentally rising from its position in the flesh, while the bridge-piece or

cross-bar connecting the prongs holds the edges of the incision in close contact.

The clamp or binder is preferably made 55 from stiff wire; but it may be made from sheet metal by stamping and afterward shaping.

To insert and withdraw the clamp or binder, I provide a gripping instrument with jaws and handles pivoted together like pincers, 60 the jaws being at such an angle to the handles that the handles are at a convenient elevation for the operator when the instrument is in use. The gripping-faces of the said jaws are roughened, grooved, or otherwise formed 65 so as to afford a good grip, and they are so relatively disposed that they are parallel to each other when they are at a distance apart equal to the thickness of the bridge-piece or cross-bar of the clamp or binder, so that they 70 grip the said bridge-piece or cross-bar throughout their length.

The accompanying drawings represent devices according to my invention.

Figure 1 shows the clamp or binder in perspective. Fig. 2 indicates by dotted lines and full lines the movement which is given to the clamp or binder in inserting and withdrawing it. Fig. 3 shows it about to be inserted in the flesh on opposite sides of an incision, and Fig. 4 shows it after it has been inserted. Figs. 5 and 6 show modifications. Fig. 7 represents the device for use in inserting and withdrawing the clamp or binder; and Fig. 8 is a cross-section of the jaws there- 85 of on the line 1 2, Fig. 7.

The sharpened prongs of the clamp or binder are marked *a*, and the bridge-piece or cross-bar connecting them is marked *b*. The said clamp or binder is shown as being made 90 of round wire; but it may be made from wire of other cross-section or the blank therefor be punched out of sheet metal. To insert the clamp or binder, its pointed prongs are placed with the points one on one side and the other 95 on the other side of the incision, (represented at *c* in Figs. 3 and 4,) the bridge-piece or cross-bar *b* being grasped between the jaws of the gripping device, Figs. 7 and 8, and a movement of rotation around the center from 100 which the curves of the prongs are struck is given to the clamp or binder, (from the dotted position to the full position in Fig. 2,) so that the prongs enter the flesh on each side of the

incision, the points of the prongs first descending and then ascending until the bridge-piece or cross-bar *b* lies close to the flesh and across the incision, as shown in Fig. 4. The bridge-piece or cross-bar *b* may be made in a line between the centers of the curves of the prongs and be connected to the prongs by continuations *b*², as shown in Fig. 5. Fig. 6 shows the bridge-piece or cross-bar *b* and the parts merging into the prongs *a* flattened to give greater lateral strength to the clamp or binder. The angles only may be thus flattened or the whole of the wire may be flattened before bending around the prongs *a*. The prongs *a* may be made of sufficient length to allow of their protruding upward from the flesh when fully inserted, so that they can be bent down to give an absolutely tight hold.

The jaws *d* *d*² of the device, Figs. 7 and 8, for use in inserting and withdrawing the aforesaid clamp or binder are made so that their inner or gripping surfaces are parallel to each other when they grip the opposite sides of the bridge-piece or cross-bar *b*. Their bearing-surfaces may be roughened or made with ridges or furrows or of waved form and preferably somewhat blunt. The jaws are set at an angle, as shown, so that the handles are in convenient position when the device is in use. The outer sides of the jaws should be rounded, as shown, and the lower or outer side of the lower jaw should be straight as well as rounded and parallel with the gripping-surface, so that when the bridge-piece or cross-bar of the clamp or binder is grasped

lengthwise between the jaws the said lower or outer side of the lower jaw constitutes a rolling bearing or fulcrum bearing on the surface, so that the instrument and clamp or binder can be rotated thereon in inserting and withdrawing the clamp or binder. The handles are preferably formed as shown, so as to afford a good hold and yet not present crevices, which cannot be easily cleaned. The joint at *e* is preferably of the kind known as an aseptic joint.

Having now particularly described and ascertained the nature of the said invention and in what manner the same is to be performed, I claim as my invention—

1. A clamp for surgical purposes, comprising semicircular prongs lying in parallel planes and curved in the same direction and a bridge-piece connecting them, substantially as described.

2. A clamp for surgical purposes, comprising semicircular prongs lying in parallel planes and curved in the same direction, a bridge-piece at right angles to the prongs and connecting them substantially at the circumference of the semicircle, said bridge-piece and prongs formed of the same strip and bent into position, substantially as described.

In testimony whereof I affix my signature in presence of two witnesses.

HAYDN BROWN.
